INVENTOR.
WILLIAM H. PEARL,

BY

G. B. Schley.
ATTORNEY.

UNITED STATES PATENT OFFICE.

WILLIAM H. PEARL, OF INDIANAPOLIS, INDIANA.

STRAIN INSULATOR.

Application filed August 6, 1924. Serial No. 730,393.

It is the object of my invention to provide a simple strain insulator mounting which can be installed with a minimum of effort and care on the part of the lineman, and which when 5 in place has its parts effectively interlocked to prevent their accidental separation; and which is inexpensive and easy to manufacture.

In carrying out my invention, I provide two mating members, preferably of identical 10 shape so that any two such parts may be used together. These two members have two fingers, one on each member, for projecting into the opposite axial ends of the bore of an insulator, with the fingers desirably overlapping 15 within the insulator bore. Each finger projects transversely from one end of an arm, which in turn projects from a perforated ear which overlaps a similar ear of the mating member so that the perforations register 20 to receive an attaching member, such as a screw-hook or a staple. The two overlapping ears of the two mating members preferably have interlocking parts, such as a finger in one projecting into a hole in the other, which 25 interlocking parts co-operate with the attaching member when the latter is in place in the perforations of the overlapping ears to prevent sufficient relative movement between the two mating members to prevent either their 30 separation or the withdrawal of the fingers from the bore of the insulator.

The accompanying drawing illustrates my invention: Fig. 1 is a plan of a strain insulator mounting embodying my invention, with 35 the insulator and the attaching screw-hook in dotted lines; Fig. 2 is a section on the line 2-2 of Fig. 1; Fig. 3 is a plan of the two mating members of the insulator mounting, separated; Fig. 4 is an end view of the strain 40 insulator mounting, showing the overlapping of the fingers within the insulator bore, the insulator itself being shown in dotted lines; and Fig. 5 is a section on the line 5-5 of Fig. 1.

The insulator 10 is desirably of the usual 45 type of porcelain insulators, with an axial bore 11 and one or more exterior circumferential grooves 12; one such groove 12 is shown in the insulator of Fig. 1, and two such 50 grooves in the insulator of Fig. 4. The groove or grooves 12 are to receive in the usual way the wire or wires which the insulator carries.

The insulator 10 is supported on the in-

wardly projecting fingers 15 of the two mating members 16 of my strain insulator mounting. The two members 16 are desirably of identical shape, so that any two such members may be used together. The two fingers 15 project into the bore 11 of the insulator 10 55 from the opposite ends of such bore, as is clear from Figs. 1 and 4. The adjacent ends of the two fingers 15 desirably overlap to form an oblique joint 17 within the bore 11, desirably at about the middle of such bore. 60 Each finger 15 projects transversely from one end of a supporting arm 18. From the other end of such arm 18 an ear 19 projects laterally on the same side as the arm 18; so that when the fingers 15 overlap, the ears 19 will 65 also overlap, and the two mating members will form a complete inclosure. The ears 19 desirably overlap in the reverse way from that in which the fingers 15 overlap; and are so arranged that the ear-faces which abut are in 70 about the medial longitudinal plane of the arms 18 and fingers 15.

The ears 19 are provided with holes 20, which register when the ears 19 of two of the mating members 16 are put together, as is 75 clear from Figs. 2 and 5. In addition, each ear 19 is provided with a lug 21 projecting from that ear-face which abuts against the mating ear, and with an opening 22 suitably arranged to receive the lug 21 of a mating 80 member when the two members are put together with their holes 20 in registry and their fingers 15 overlapping. The lugs 21 and holes 22 are eccentrically located with respect to the holes 20, so that when they are in 85 engagement they prevent turning of the two members 16 relatively to each other about the common axis of the two registering holes 20. Conveniently the hole 22 is merely a lateral extension of the hole 20, at one side, as 90 that facilitates manufacture. In addition, the lugs 21 are preferably of somewhat greater length than the thickness of the ears 19, as is clear from Fig. 5, to insure against their 95 separation from the holes which receive them.

When two mating members 16 are put together with their holes 20 in registry and their fingers 15 overlapping, a suitable attaching member may be inserted through the 100 registering holes 20 to hold them in registry and to furnish the support for the structure 105 as a whole. Such an attaching member may

be of any suitable nature, such as a screw hook 25 as illustrated in Figs. 1 and 2. This screw hook is merely an example of a suitable attaching member, and my invention is not limited to this particular attaching member. 5

The operation of installing my strain insulator mounting is very simple. As the members 16 are desirably all alike, the line-man merely uses any two of such members for 10 an installation. He inserts the fingers 15 of two members 16 into opposite axial ends of the insulator 10, by the same motion putting the two ears 19 in overlapping position; and then he swings the two ears together so that 15 the lugs 21 project through the holes 22, with the holes 20 in alinement. Then he inserts the attaching member 25 through these registering holes 20 of the assembled unit composed of the two mating members 16 and the 20 insulator 10. If the attaching member is a screw hook, it may already have been screwed into the support on which the strain insulator is mounted.

When the device is thus assembled and 25 mounted, it remains in place, with its various parts in proper relative position, under all conditions encountered, and can only be taken down by direct intention. The interlocking provided by the attaching member 25 and 30 the lugs 21 and holes 22 prevents the fingers 15 from being withdrawn from the bore of the insulator. Such withdrawal can only be obtained by first separating the attaching member 25 from the pair of members 16. If 35 the wire that the insulator supports should break, the unit comprising the two members 19 and the insulator 10 merely drops down by gravity, while remaining on the hook 25, without letting the insulator 10 fall off. If 40 the insulator 10 is broken for any reason, the overlapping fingers 25 catch the wire which was fastened in the groove 12 of the insulator, and thus keep it from falling.

I claim as my invention:—

1. A strain insulator mounting, comprising two mating members having fingers arranged to extend into an insulator bore from opposite ends thereof; said two mating members being arranged to overlap each other outside of said insulator, and the overlapping parts of said members being provided with registering holes for receiving an attaching member, the overlapping portions of said two mating members being provided with interlocking parts for preventing relative turning 55 of said two members. 45

2. A strain insulator mounting, comprising two substantially similar members, each of said members having a head portion and a finger portion, said finger portions being adapted to overlap, each of said head portions being provided with a locking lug and with a depression for receiving the locking lug on the other of said members. 50 60

3. A strain insulator mounting, comprising two mating members adapted to be assembled in substantially co-planar relation, said two members having portions which overlap when the members are assembled, said overlapping portions being provided with locking 70 means for preventing relative movement of said two members in their plane, and said members having extending portions adapted to receive and hold between them an insulator. 75 65

4. A strain insulator mounting as set forth in claim 3 with the addition that the overlapping portions of said members are provided with registering holes for receiving an attaching member. 80

In witness whereof, I have hereunto set my hand at Indianapolis, Indiana, this 2d day of August, A. D. one thousand nine hundred and twenty-four.

WILLIAM H. PEARL.
